Inventor,

Oliver J. Mattax

UNITED STATES PATENT OFFICE.

OLIVER J. MATTAX, OF WASHINGTON, PENNSYLVANIA.

RECLINING-CHAIR.

SPECIFICATION forming part of Letters Patent No. 728,264, dated May 19, 1903.

Application filed May 24, 1901. Serial No. 61,731. (No model.)

To all whom it may concern:

Be it known that I, OLIVER J. MATTAX, a citizen of the United States, residing at Washington, county of Washington, and State of Pennsylvania, have invented certain new and useful Improvements in Reclining-Chairs; and I do hereby declare the following to be a full, clear, and exact description of the invention, such as will enable others skilled in the art to which it appertains to make and use the same.

This invention has relation to new and useful improvements in reclining-chairs of that kind or type comprising movable back, seat, and foot sections, which are so arranged and capable of such adjustment with relation to each other as to permit of their assuming various positions to suit the comfort or desires of the occupant.

The primary object of the invention is to construct a chair of the character mentioned which will be simple in construction and wherein the back, seat, and foot sections will be capable of simultaneous adjustment or wherein the back-section may be disconnected from the foot portion and the seat and foot section thereby permitted to remain stationary independent of the back-section.

A further object is to provide a joint or coupling for connecting the back and foot sections which will be so constructed as to hold the said sections rigidly connected and which may be broken or operated to connect the sections to permit of their independent movement.

The invention consists in the arrangement and combination of the elements to be more fully described hereinafter, and the novelty of which will be particularly pointed out and distinctly claimed.

With this object in view I will now describe my invention, which is as follows:

Referring to the drawings, Figure 1 is a perspective view of my invention. Fig. 2 is a perspective view in detail of the adjustable joint employed. Fig. 3 is a transverse sectional view of the joint, and Fig. 4 is a side elevation in detail of the hinged joint in the open position.

Similar letters of reference indicate corresponding parts in the different figures of the drawings.

A designates the supporting-frame of the chair, upon which are mounted and secured the various elements constituting my invention. 55

This frame consists of two side portions, which are duplicates in their structure and which have secured thereto metal arms B, which may be of any desired configuration. 60 The seat C is made separate from the frame A and is adapted to be pivoted or hinged, as hereinafter described. The back and foot rest are formed of two bent pieces D and D', suitably hinged or connected together, as will 65 be more fully described hereinafter. The rear of the seat C is hinged to a metal bar, so as to admit of it being folded against the back. Said iron bar runs through the rails from one side to the other, the ends of which 70 rest in grooves a, formed on the inner sides of the frame A. The forward end of the seat rests upon a rod or bar b, which in turn is secured in eyelets or braces c, which eyelets or braces are secured in or to the arms B. Underneath the foot-rest is a trip d, which engages with a rack e, the purpose of which is for raising or lowering the rest, thus adapting it to suit the person occupying the chair. 75

The rails or bent pieces D and D' are hinged 80 together at e' for the purpose of admitting the back to be reclined independent of the foot-rest. The construction of the hinge is as follows: The hinge embraces the rails or bent pieces D and D', and the part which is secured 85 to the foot-rest or shortest section of the rail is slotted for the purpose of allowing the ends of a metal pin e'', which is secured to part D, to play therein, the purpose of which will appear hereinafter. The inner side of this 90 section is formed with a longitudinal cavity f for the purpose of retaining a spiral spring g. The upper end of this section of the hinge is bridged, as shown at h, and provided with a set-screw i, which is adapted to engage with a nut j, which is embedded in the rail D for the purpose of holding or locking the hinge fast with said rail, or I may substitute a spring-latch (not shown) for the purpose of locking the hinge fast. When it is desired to recline the back 100 independent of the foot-rest, all that is necessary to be done is to unscrew the set-screw i, which will allow the back to recline independent of said foot-rest. When in this po-

sition, the portion of the hinge carrying the set-screw will assume an almost vertical position, caused by the pin sliding in the slots of the said hinge and compressing the spring 5 *g*, as shown in Fig. 4. This hinge *e* is permanently secured to the section of rail *D* carrying foot-rest. The spiral spring *g* in the concave portion of the hinge acts to help return the hinge and rail to their normal position.

Having described my invention, what I claim is—

In a reclining-chair, the combination of a

supporting-frame, a seat-section, a back-section pivoted in the frame, a foot-rest section 15 adjustably hinged to the back-section, and means for locking the foot and back sections, together with means for holding the foot-section stationary, permitting the back-section to be reclined independently of the foot-section, substantially as shown and described. 20

OLIVER J. MATTAX.
